UNITED STATES PATENT OFFICE.

ANTHONY GIARDINO, OF BROCKTON, MASSACHUSETTS.

HANDLE.

1,246,587.

Specification of Letters Patent. Patented Nov. 13, 1917.

Application filed June 13, 1916. Serial No. 103,428.

To all whom it may concern:

Be it known that I, ANTHONY GIARDINO, a citizen of the United States, residing at Brockton, in the county of Plymouth and State of Massachusetts, have invented certain useful Improvements in Handles, of which the following is a specification, reference being had therein to the accompanying drawing.

10 This invention relates to improvements in handles, one object of the invention being the provision of a collapsible handle for attachment to bundles and the like, and which may be readily placed in the vest pocket 15 when not in use, and which is provided with swingingly mounted means that are normally concealed for engagement with the bundle fastener.

In the accompanying drawings:—

20 Figure 1 is a perspective view of the complete device with the various elements thereof extended.

Fig. 2 is a perspective of all of the elements concealed and the members collapsed, 25 and

Fig. 3 is a longitudinal sectional view through one of the hand grip forming members showing the construction of one of the hooks.

30 Referring to the drawings, the numerals 10 and 11 designate the cylindrical members, each one of which is slotted as at 12 and 13 for the reception of the coupling member 14 which is pivotally connected in place by 35 means of the pins 15. This coupling member is acted upon by the springs 16 to normally hold the parts either extended or collapsed as illustrated.

Each member is further provided with the 40 socket or recess 17 in which is mounted the spring 18 to abut the shouldered or cam end 19 mounted for swinging movement upon the pin 20.

Detachably connected to the pivoted cam end is a hook 22 having the spring catch 23 45 by means of which the accidental releasing of the cord or other means connected to the hook is prevented.

The member 11 is provided with the longitudinal bore 36 which has slidably 50 mounted therein the reduced shank 37 of the button hook 38.

From the foregoing description, it is evident that with a device of this character, a very handy tool is provided which can be 55 carried in the vest pocket when collapsed, and which can be readily extended to permit the use of the bundle engaging hooks for the purpose of holding any package or article. 60

What I claim as new is:—

In combination, a pair of similarly shaped cylindrical members, one end of each of said members being slotted and having the edges facing the slots curved, a coupling bar 65 projecting into the said slots, a flat spring projecting longitudinally in each slot and secured in the back wall thereof, pivot pins passing through the slotted ends of said members and through the opposite ends of 70 said coupling bar and holding the inner edge of said bar in contact with the two springs and also causing the curved edges of said members to abut and allowing one member to swing down to a substantially parallel 75 position opposite the other member, and a hook carried by each member at its opposite end, said flat springs being tensioned so as to rise against the opposite ends of said coupling bar as one of the members is swung 80 opposite the other member.

In testimony whereof I affix my signature.

ANTHONY GIARDINO.
